Patented Apr. 1, 1919.

By his Attorney *Edward J. Brooks*

UNITED STATES PATENT OFFICE.

EDWARD J. BROOKS, OF EAST ORANGE, NEW JERSEY.

STRAP-TIGHTENING TOOL.

1,299,113.

Specification of Letters Patent.

Patented Apr. 1, 1919.

Application filed October 28, 1918. Serial No. 259,909.

To all whom it may concern:

Be it known that I, EDWARD J. BROOKS, a citizen of the United States, and a resident of East Orange, in the county of Essex and State of New Jersey, have invented certain new and useful Improvements in Strap-Tightening Tools, of which the following is a specification.

The present invention relates generally to strap tightening tools for tightening the overlapped ends of a metallic or other strap passed around a box or other container, and has for its main object a simple and reliable means for acting upon the strap ends to effectively tighten the strap.

In the accompanying drawings the invention is shown in a concrete and preferred form in which—

Figure 1 is a vertical sectional view on the line 1—1 of Fig. 2 of a tightening tool embodying the invention, the strap tightening means being shown at the end of its feeding stroke.

Fig. 2 is a top plan view of the parts shown in Fig. 1.

Fig. 3 is a fractional view of the parts shown in Fig. 1, with the strap tightening means at the end of its return stroke.

1 indicates a support here forming the base of the tool from which rises the sidewall 2 having an end portion 3 terminating short of the base as shown to provide an opening 4 for the ends of the strap. Secured to the end portion 3 is a second sidewall 5 also terminating short of the base portion to provide opening 6 so that the base can be slipped under the strap ends.

7 is a rotatable member conveniently mounted for free rotation on stud 8 and provided with a segment 9 slidably mounted by means of pins 10 and elongated slots 11. 12 is an actuating means in the form of a handle mounted to rotate on stud 8 and extends out through the opening 13 of member 7. 14 is a cam formed on the lower end of 12 and acting against sliding segment 9. When handle 12 is turned from the position shown in Fig. 3 to the position shown in Fig. 1, cam 14 will engage segment 9 and move it outwardly at the same time rotating member 7. This feeding stroke will cause segment 9 to tighten the strap whose overlapped ends 15 are on the support. When handle 12 is moved from the position shown in Fig. 1 to the position shown in Fig. 3, cam 14 will, before member 7 commences

backward rotation, disengage segment 9 thereby permitting the latter to move inwardly as member 7 returns.

To prevent retrograde movement of the strap during the return stroke of member 7 there is provided a pivotally supported detent 16 mounted at 17 and normally held in engagement with the strap ends by reason of spring 18 bearing against pin 19 on the 60 detent, the spring pressure being of such a character that tightening of the strap ends under the influence of the action of member 7 may take place but retrograde movement is prevented.

20 indicates a latch pivotally supported at 21 which when moved into the dotted line position shown in Fig. 1 will act against pin 19 and lift detent 16 out of engagement with the strap ends and will remain in such position because outer end 22 of said latch will have passed over the vertical center line of pin 19 and consequently spring 18 will hold the parts in this position. To restore detent 16 to engagement with strap 15 latch 80 70 75 20 is moved into the full line position shown in Fig. 1 when spring 18 will automatically press detent 16 against the strap.

The supporting member 1 may be provided with a roughened upper surface as is 85 customary in devices of this character or as herein shown it may be provided with adjustable surface members 23 seated in openings 24 of the base portion and adjustable by means of screws 25, the head of each 90 screw being located between member 23 and plate 26, said plate being secured to member 23 by means of pins 27. 28 indicates a handle portion which as shown in Fig. 2 is 95 bifurcated at its outer end and thus straddles the strap portions when the device is placed upon a container to which the strap is to be applied so as not to interfere with movement of the strapping when tightening the same. It will be further understood that the left hand of the operator may be placed flatwise upon said handle and that handle 12 may then be manipulated by means of the right hand of the operator.

One of the characteristic features of the 105 tool is that the tightening operation may be reversed at any point, so that any length of feeding stroke smaller than the greatest one of which the tool is capable may be obtained. This is frequently of great advantage after 110 the tool has been manipulated a number of times to tighten a strap around a bale, since

the length of the final tightening movement required is usually an indeterminate one and it will be understood that, if a pawl and ratchet device is used, the feeding movement 5 can never be less than the space of a ratchet tooth and that all other feeding strokes will be multiples thereof.

I claim:

1. A strap tightening tool comprising: a 10 support for overlapped strap ends and strap tightening means including a rotatable member, a segment slidingly mounted on said rotatable member, and means for imparting a sliding movement to the segment 15 and a rotating movement to the rotatable member.

2. A strap tightening tool comprising: a 20 support for overlapped strap ends and strap tightening means including a rotatable member, a segment slidingly mounted on

said rotatable member, and means for imparting an outward sliding movement to the segment when moving the rotatable member in one direction and admitting of an inward sliding movement thereof when moving the 25 rotatable member in the opposite direction.

3. A strap tightening tool comprising: a support for overlapped strap ends, and strap tightening means including: a rotatable member, a segment slidingly mounted on 30 said rotatable member, rotatable operating means movable independently of the rotatable member at the beginning of its stroke to cause outward movement of the segment and thereafter engaging said rotatable member to effect a turning movement thereof.

Signed at New York city, in the borough of Manhattan, in the county and State of New York, this 22d day of October, 1918.

EDWARD J. BROOKS.
